FURNACE DOOR OR THE LIKE

Raymond B. Groetzinger, Pittsburgh, Pa., assignor to Blaw-Knox Company, Pittsburgh, Pa., a corporation of New Jersey

Application April 1, 1944, Serial No. 529,059

3 Claims. (Cl. 122—498)

1

This invention relates to a furnace door and, in particular, to a water-cooled door having a refractory lining or protective layer over the inner face thereof.

The placing of the refractory lining in such doors is frequently done by the purchaser and not necessarily by the manufacturer of the hollow metal panel or of the refractory, these being usually furnished separately. The metal panel may be relined with refractory by the purchaser, or the lining may be patched or repaired, the panel being in the nature of a permanent structure and the lining, although in my invention having a much longer life than in any other doors, is subject to deterioration in use and may ultimately be replaced with a new one. My invention relates particularly to an improved hollow metal door panel as an article of manufacture.

It has been quite general heretofore to provide furnace doors, such as those used for open-hearth furnaces, comprising a hollow metal panel arranged for water cooling and a layer of refractory material extending over one face thereof, with heat-conducting means, such as metal studs, projecting from the inner wall of the panel into the lining, to absorb heat from the lining and also to anchor it mechanically to the metal panel or back of the door. This prior construction is described in Fuchs Patent 2,325,945, which also discloses the using of studs or shelves of a conductive refractory instead of metal studs. Whether the studs are of metal or of refractory material, they cool the lining to a limited extent only; and when the studs or other supports become exposed due to the face of the lining being gradually consumed, the supports are themselves damaged and must be replaced when a new lining is applied. The object of this invention is to improve upon the prior construction referred to above and to provide a longer life for the lining by maintaining it at considerably lower temperature and also to provide a permanent anchorage for the lining to the back of the door which can be relined indefinitely with plastic refractory.

In a preferred embodiment, my invention comprises a furnace door or the like composed of a water-cooled panel or back provided with a refractory lining or protective layer in which are embedded a plurality of pipe lengths, either straight or variously bent having their ends secured to the inner wall of the door panel and communicating with the interior thereof. The straight pipes are secured at one end only; the bent pipes are secured at both ends. By this

2

construction, the cooling water supplied to the interior of the door panel or back flows into the pipe lengths, thereby serving both to absorb heat from the lining and to protect the pipe lengths from burning when exposed to the furnace gases. The pipe lengths also serve to hold the lining in place on the door. The pipe lengths, or at least some of them, may be disposed at an angle to the horizontal so that gravity circulation of water therethrough is obtained.

Further details and novel features of the invention will be explained during the following complete description of the preferred embodiment and a modification which refer to the accompanying drawings. In the drawings,

Figure 1 is an elevation of the interior face of one form of door with the lining omitted from all but a portion thereof;

Figure 2 is a vertical section taken along the plane of line II—II of Figure 1;

Figure 2A is a partial sectional view taken along the line of IIA—IIA of Figure 1;

Figure 3 is a view similar to Figure 1 showing a modification; and

Figures 4 and 5 are transverse sections taken along the planes of lines IV—IV and V—V, respectively, of Figure 3.

Referring in detail to the drawings and, for the present, to Figures 1 and 2, the embodiment of my invention there illustrated is a furnace door comprising a double-walled metal panel or back 10 having an inwardly extending marginal flange 11 and a lining or protective layer 12 of refractory material substantially filling the space defined by the flange 11. The door has a lifting eye 13 and lugs 14 to which operating links may be pivoted. An inlet connection 15 for cooling water has a pipe 16 extending downwardly therefrom through the panel 10 at one side to a point near the bottom while an outlet connection 17 is located at the top of the panel on the other side. Clean-out holes 18 in the sides of the door near the bottom are provided with removable plugs.

The door back or panel 10 is preferably fabricated from plate, being composed of spaced walls connected by staybolts 19. A wicket or peep-hole 20 in the form of a length of tube extends through the door near the bottom. A sleeve 21 having a diameter somewhat greater than that of the wicket provides a jacket for cooling water around the inner end of the latter.

A plurality of pipe lengths 22a, 22b, 22c, and 22d of yoke or U-shape are disposed on the inner face of the panel 10 within the space defined by

the flange 11, having their ends secured as by welding to said face at spaced points thereon at which holes 23 are formed whereby the pipe lengths communicate at each end with the interior of the panel 10. As shown in Figure 1, the pipe lengths are disposed at various angles to the horizontal, the pipe lengths 22a and 22b, for example, being at an angle of about 50°, the pipes 22c at an angle of 90° while the pipes 22d are substantially horizontal. As shown in Figure 2, the pipe lengths are wholly embedded in the lining 12 which is substantially flush with the inner face of the flange 11.

Extending inwardly from additional holes 23 in the side flanges 11 are a plurality of straight pipes or hollow studs 24, opening into the body of the interior of the door panel and closed at their outer ends. On the upper and lower flanges 11 and around the greater part of the circumference of sleeve 21 are provided and secured at other holes 23 a plurality of L-shaped pipes 25, a substantially horizontal arm of which enters and is welded to the inner face of panel 10 at other holes 23 providing an opening into the body of the panel, the other arm communicating with the interior of the flanges of 11 and 20 (see Figs. 2 and 2A). Extending diagonally from the lower portion of 21 into lower flange 11 are two straight pipes 26, spaced from the back of the door.

The pipe lengths 22a, 22b, etc., 24, 25 and 26 perform two functions. In the first place, they serve mechanically to anchor the lining 12 to the door back or panel 10 and prevent falling out of portions thereof even should the lining become badly cracked. The other function of the pipe lengths is to remove heat from the lining 12, thus lessening the likelihood of injury thereto resulting from overheating and reducing the tendency to cracking as a result of expansion and contraction. This is accomplished by maintaining the pipe lengths full of cooling water through their connections to the panel 10. This improvement greatly increases the life of the lining. In addition, the presence of water in the pipe lengths cools them below the temperature at which they become burned or consumed after the lining, near the end of its life, no longer covers them completely, so that the door may be relined with refractory without having first to replace the anchorage structure.

The pipes are all disposed so as to provide an outlet for generated steam into the body of the door without trapping the steam within the pipes. The studs 24 all open above or at the same level as the highest portion of their interior. The L's 25 provide steam outlets at their highest points. The yokes 22a, 22b, and 22c provide an outlet above the point of water inlet, while in yokes 22d steam may escape at either end without being trapped in the yoke. Circulation of water through the yokes by thermo siphonic action is provided in pipe lengths 22a, 22b, 22c and 25, which make up the majority of the anchorages for the lining. This increases somewhat the effectiveness of the cooling of the lining. In the other pipe lengths, the steam bubbles set up circulation; and the arrangement provides, at least, that water will enter and cool the yokes as fast as steam is generated.

A modified form of door illustrated in Figures 3 through 5 is generally similar to that described above. It comprises a double-walled panel or back 30 having an inwardly extending marginal flange 31 and a lining or protective layer of refractory material 32 applied thereto. In the lining

are embedded pipe lengths 33 and 34 having their ends secured to the inner wall of the panel and communicating with the interior thereof. In general, the modified form of door differs from the form first described in that the panel 30 is convex exteriorly instead of substantially flat as in the case of the door in Figures 1 and 2. The pipe lengths 33, furthermore, extend substantially the full width of the door and are arranged at a small angle to the horizontal. The pipe lengths 34 are of such length as to be accommodated between the sides of the door and the wicket 35 which is generally similar to that shown at 20. It will be apparent that the pipe lengths 33 and 34 perform the same function as the pipe lengths 22a, 22b, etc., viz., cooling the lining 32 by permitting the circulation therethrough of cooling water supplied to the door panel or back and mechanically securing the lining in place on the panel.

It will be apparent from the foregoing description that my invention provides a furnace door having marked advantages over previously known constructions. The pipe lengths embedded in the refractory lining on the inner face of the door provide much more effective cooling for the lining than the heat-conducting studs welded to the inner face of the lining used heretofore. The danger of burning the lining or of sagging thereof as a result of overheating is entirely avoided. The pipe lengths also have a more effective mechanical interlock with the lining than the metal studs and the possibility of any portion of the lining falling out is practically eliminated even though the lining as a whole should become badly cracked. The cooling pipes, being wholly embedded in the lining, are protected from the high temperature existing on the inside of the furnace.

Doors constructed in accordance with the invention, when installed on an open-hearth furnace, have demonstrated their ability to withstand a number of heats much greater than that of which the best doors of previous construction were capable, without requiring any maintenance beyond the occasional application of a small amount of lining material as may be necessary at points on the exposed surface thereof where slight spalling occurred.

Although I have illustrated and described but two forms of the invention, it will be recognized that changes in the details of the construction illustrated may be made without departing from the spirit of the invention or the scope of the appended claims. The metal panel or back of the door, for example, instead of being continuous, may be of the grid type shown in Williams Patent 1,690,606, and the word "panel" as used in the claims is intended to include such type.

I claim:

1. In a water-cooled hollow metal furnace door for an open-hearth furnace or the like, a hollow double-walled panel having a generally vertical inner wall and a generally vertical back between which a relatively large volume of cooling water is adapted to be circulated, said panel further having a hollow peripheral inwardly extending marginal flange defining with the inner face of said inner wall a refractory lining space of a predetermined thickness adapted to be filled with a plastic refractory lining, a plurality of relatively short cooling water pipe lengths in a predetermined pattern connected to said inner wall and extending inwardly thereof to lie within said lining space, at least some of said pipe lengths being at an angle to the horizontal, said pipe lengths having the respective

ends thereof opening into the interior of said hollow double-walled panel, said pipe lengths further extending relatively close to the plane defined by the face of said flange, whereby said pipe lengths interlock, anchor and cool said refractory lining during the service thereof.

2. In a water-cooled hollow metal furnace door for an open-hearth furnace or the like, a hollow double-walled panel having a generally vertical inner wall and a generally vertical back between which a relatively large volume of cooling water is adapted to be circulated, said panel further having a hollow peripheral inwardly extending marginal flange defining with the inner face of said inner wall a refractory lining space of a predetermined thickness adapted to be filled with a plastic refractory lining, a plurality of relatively short generally U-shaped cooling water pipe lengths in a predetermined pattern connected to said inner wall and extending inwardly thereof to lie entirely within said lining space, substantially all of said pipe lengths lying in planes generally normal to said inner wall, substantially all of said pipe lengths further being at an angle to the horizontal and having the respective ends thereof opening directly into the interior of said hollow double-walled panel, said pipe lengths further extending relatively close to the plane defined by the face of said flange, whereby said pipe lengths interlock, anchor and cool said refractory lining during the service thereof.

3. In a water-cooled hollow metal furnace door for an open-hearth furnace or the like, a hollow double-walled panel having a generally vertical inner wall and a generally vertical back between which a relatively large volume of cooling water is adapted to be circulated, said panel further having a hollow peripheral inwardly extending marginal flange defining with the inner face of said inner wall a refractory lining space of a predetermined thickness adapted to be filled with a plastic refractory lining, a plurality of relatively short generally U-shaped cooling water pipe

lengths in a predetermined pattern positioned at different places across said inner face of said inner wall relative to the height and width thereof and at an angle to the horizontal, said pipe lengths having their respective intermediate portions spaced inwardly from said inner wall to lie entirely within said lining space and further spaced from each other, said pipe lengths further having the respective ends thereof opening into the interior of said hollow double-walled panel, said pipe lengths further extending relatively close to the plane defined by the face of said flange, whereby said pipe lengths form yokes which interlock and anchor said refractory lining and respectively permit cooling water to circulate therethrough by thermo-siphonic action.
